Term of patent 14 years

(Cl. D18—2)

FIG. 1 is a perspective view of a modular building unit showing my new design;

FIG. 2 is a top plan view of the modular building unit shown in FIG. 1;

FIG. 3 is a bottom plan view of the modular building unit shown in FIG. 1;

FIG. 4 is a perspective view of a modified form of the modular building unit shown in FIG. 1;

FIG. 5 is a top plan view of the modular building unit shown in FIG. 4;

FIG. 6 is a bottom plan view of the modular building unit shown in FIG. 4;

FIG. 7 is a perspective view of another modified form of the modular building unit shown in FIG. 1;

FIG. 8 is a top plan view of the modular building unit shown in FIG. 7;

FIG. 9 is a bottom plan view of the modular building unit shown in FIG. 7;

FIG. 10 is a perspective view of another modified form of the modular building unit shown in FIG. 1;

FIG. 11 is a top plan view of the modular building unit shown in FIG. 10;

FIG. 12 is a bottom plan view of the modular building unit shown in FIG. 10;

FIG. 13 is a perspective view of another modified form of the modular building unit shown in FIG. 1;

FIG. 14 is a top plan view of the modular building unit shown in FIG. 13; and

FIG. 15 is a bottom plan view of the modular building unit shown in FIG. 13.

My invention is characterized by the provision of a rectangularly shaped building unit having two cores extending therethrough and provided with corresponding projections and recesses on its upper and lower faces, respectively, and pairs of juxtaposed projections and recesses on at least one of its side faces.

I claim:

The ornamental design for a modular building unit, as shown and described.
